P. DUNN.
GRINDING WHEEL FOR GRANITE.
APPLICATION FILED MAY 27, 1913.

Patented Sept. 2, 1913.

UNITED STATES PATENT OFFICE.

PATRICK DUNN, OF NEW YORK, N. Y.

GRINDING-WHEEL FOR GRANITE.

1,072,216.

Specification of Letters Patent.

Patented Sept. 2, 1913.

Application filed May 27, 1913. Serial No. 770,141.

To all whom it may concern:

Be it known that I, PATRICK DUNN, a citizen of the United States, and a resident of the city of New York, Long Island City, 5 borough of Queens, in the county of Queens and State of New York, have invented a new and Improved Grinding-Wheel for Granite, of which the following is a full, clear, and exact description.

10 Among the principal objects which the present invention has in view are: to provide for feeding the chilled steel shot to the block wheel while the same is rotated; to accomplish the above purpose without scattering the shot or cutting material; to provide means for preventing the scattering of the grinding material, and the consequent loss of time; and to provide means for securing the iron to a wheel, so that the same 15 does not become loosened.

Reference is to be had to the accompanying drawings forming a part of this specification, in which similar characters of reference indicate corresponding parts in all 20 the views, and in which—

Figure 1 is a perspective view of a wheel constructed and arranged in accordance with the present invention; Fig. 2 is a vertical section taken on the line 2—2 in Fig. 3; 25 Fig. 3 is a vertical section taken on the line 3—3 in Fig. 2; and Fig. 4 is a bottom plan view of the wheel.

As shown in the accompanying drawings, the tool consists primarily of a wheel 9. 30 The wheel 9 is provided with a central hopper formed by upstanding flanges 10 flared upwardly and outwardly, as best seen in Figs. 1 and 3 of the drawings. The wheel 9 is also perforated to receive the threaded 35 shanks 11 of anchor bolts 12. The anchor bolts 12 are tapered and square in cross section, as seen in Figs. 3 and 4 of the drawings, to fit corresponding recesses provided in the block 13.

40 The block 13 is preferably constructed from soft steel, and is formed as a solid structure, having an average thickness of approximately four inches. The block is circular in shape, conforming accurately to 45 the dimensions of the wheel 9, and is provided with a series of radially-disposed grooves 14. The grooves 14 are triangular in cross section, the pitch of the angle being set back, or, in other words, the opposite 50 sides of the grooves are both inclined backward from the rotary-path direction in

which the block 13 is normally moved. The grooves 14, as seen in Fig. 4 of the drawings, are freely opened to a central space 15. The space 15 is formed by the inclined walls of 60 the block 13, which walls are inclined oppositely to the inner walls of the flange 10. The walls of the flange 10 and of the block 13 form a pocket or hopper for receiving and for holding loosely the abrasive material 65 with which the wheel is provided. The wheel 9 and block 13 are rotated in service, being connected for this purpose with a power source by a transmission shaft, the connection being formed by vertical brackets 18, 18. Said shaft is perforated to receive and pass therethrough a bolt 20. The connection formed by means of the bolt 20 is what may be termed a temporary connection, it being designed that when the 70 iron is not employed, it may be disconnected from the transmission shaft. For this purpose, the end of the bolt 20 is provided with an elongated slot, through which may be driven the wedge pin 21. 75

The head 17 is integrally connected with a cross bar 22, this being effected by the intermediate pedestal 23. At each end of the cross bar 22, a squared portion 24 is produced for seating between a square recess 80 having parallel faces formed in the two sections of the flange 10, shown best in Fig. 1 of the drawings.

To hold the cross bar 22 in position, there are provided bolts 25, with nuts 26 and an anchor head 27. The heads 27 are seated in reamed ends of perforations formed in the wheel 9, while the bolts extend upward, to be threaded through perforations provided therefor in the cross bar 22. 95

It will be noted that the upper edge of the cross bar 22 is tapered, to present a shedding upper surface to guide the steel shot generally used in this trade for cutting the stone, into the open space 15, the overhung walls whereof then serve to prevent the throwing of the shot out of said recess. It will also be observed that the upper edge of the bar 22 is below the edge of the flange 10. This construction, using the head 17 100 and the pedestal 23 centrally located and united to the bar 22, provides a clear space between said head and flange 10, wherein may be poured the shot during the rotation of the wheel 9 and block 13. The pouring 105 of the shot, when using such a construction, is not accompanied by the usual seat-

tering thereof. The saving effected by the use of a wheel where the shot may be poured into the center thereof, to be distributed therefrom by the radially-disposed grooves, 5 must be obvious. The centrifugal action of the wheel tends to throw the shot outward to the perimeter of the block 13. This tendency insures a constant charge for the grooves 14. The grooves 14 being closed 10 at the upper ends, the shot is prevented thereby from flying beyond the wheel, to be scattered or lost thereby, or, if unnoticed, to remain upon the stone, marring the surface thereof, and thereby requiring an extra amount of finishing by the carborundum 15 and buffing wheels which follow the operation performed by the ironing wheel herein described.

If desired, any form of cap or hood may 20 be used in conjunction with the wheel 9, which, riding or resting yieldingly upon the stone outside the periphery of the block 13, prevent the escape of any particles of the shot thrown or scattered by the block 13.

25 Having thus described my invention, I claim as new and desire to secure by Letters Patent:—

1. A wheel as characterized, comprising an open-centered ring grinding block, said 30 block being provided with a series of radially-disposed grooves, said grooves being closed at the outer end and open at the inner end; a wheel having an upstanding flange surrounding the open center of said ring

block to form a hopper to receive grinding 35 particles; a coupling head having upstanding brackets spaced apart to receive a rotary shaft for revolving said wheel; and a cross bar rigidly connected with and extended between the lower edges of said flange, said 40 bar being operatively connected with said head by a relatively small and centrally-disposed pedestal, said head overhanging said pedestal to form a cap therefor and to form in conjunction with said flange an angular free opening for said hopper. 45

2. A wheel as characterized, comprising an open-centered ring grinding block; a wheel for supporting same; means for rigidly fastening said wheel and said block; 50 a centrally-disposed upwardly-extending hopper mounted on said wheel; a bar extending across said hopper, said bar being maintained at a level below the upper edge of said hopper; and a coupling head rigidly 55 connected with said bar by means of a relatively small, centrally-disposed pedestal, said head being extended beyond the side of said pedestal to form a hood-like overhang for said hopper.

In testimony whereof I have signed my name to this specification in the presence of two subscribing witnesses.

PATRICK DUNN.
